Inventor:

Charles W. Holbrook

By Noratus E. Breloone

Attorney:

UNITED STATES PATENT OFFICE.

CHARLES W. HOLBROOK, OF PROVIDENCE, RHODE ISLAND, ASSIGNOR TO HOLBROOK
RAW HIDE COMPANY, A CORPORATION OF RHODE ISLAND.

MALLET.

1,276,218.

Specification of Letters Patent. Patented Aug. 20, 1918.

Application filed May 17, 1918. Serial No. 235,067.

To all whom it may concern:

Be it known that I, CHARLES W. HOLBROOK, a citizen of the United States, residing at Providence, in the county of Providence and State of Rhode Island, have invented certain new and useful Improvements in Mallets, of which the following is a specification.

My invention relates to loaded rawhide mallets of which my former United States Patent No. 463,113, issued Nov. 10, 1891, is a type.

In this type of mallet wherein a metal strip was interwound it was necessary that the metal should not extend to the working faces of the mallet because it would scratch the work. The resultant spiral openings in the working faces were so broad as to require a filling which pulverized with use and escaped. When through the working faces were worn to the metal the mallet was useless. In this type of mallet it was necessary that the hide to be rolled be of uniform thickness, both transversely and in the direction of rolling. This involved the necessity of using selected hides as well as of shaving the surface of the same to a uniform thickness. Furthermore it was necessary to make the diameter of the head excessive in order to secure the necessary weight.

The essential objects of my invention are to overcome the disadvantages herein above enumerated; to arrange the weight or load in the head so that it shall be effective at the point where the blow occurs; to vary the weight of the head without varying the size, and capable of delivering either a yielding or heavy blow; to improve the balance and feel, and to attain these ends in a structure requiring a minimum of rawhide, which is scarce, in its construction.

To the above ends essentially my invention consists in such parts and combinations of parts as fall within the scope of the appended claims.

In the accompanying drawings which form a part of this invention,

Figure 1 is a side elevation of my novel mallet,

Fig. 2, an enlarged longitudinal section of the head with a portion of the handle broken away, and

Figs. 3 and 4, transverse sections of the

same on lines 3—3 and 4—4 respectively of Fig. 2.

Like reference characters indicate like parts throughout the views.

My mallet comprises a cylindrical metallic core 6, preferably of lead, having a transverse hole 7 to receive the handle 9. Around this core is formed a sheath 10 of rawhide formed from a strip which need be of uniform thickness transversely of the rolling only, but may be of any thickness in the direction of the rolling. This strip is spirally rolled or wound around the core in convolutions 11, and is affixed thereto by compression and an adhesive in a manner known in the art. The resultant sheath or shell extends beyond both ends of the metallic coils 70 forming sockets 12 for rawhide cores now to be described.

Each core 13 consists of a spirally wound strip of rawhide having the contacting faces of the convolutions 14 covered with cement. 75 The wound member 13 is suitably compressed, dried, and driven into the sockets 12, with their ends flush with the ends of the sheath. In this instance the cores 13 are insured against accidental escape by rivets 80 16 transversely traversing the sheath and cores through openings 17 and 18 respectively.

The sheath has openings 19 in alignment with the hole 7 to admit the handle 9.

I claim:

1. In a mallet of the type set forth, the combination of a metallic core, a rawhide sheath surrounding the core and projecting beyond the ends thereof forming sockets, 90 rawhide cores seated in the sockets, and a handle fast in the sheath and metallic core.

2. In a mallet of the type set forth, the combination of a metallic core, a sheath comprising spiral convolutions of rawhide 95 tightly embracing the core and extending beyond the core, cores comprising spiral convolutions of rawhide fast in the extended portions of the sheath and in contact with the metallic core, and a handle in the sheath and metallic core.

3. In a mallet of the type set forth, the combination of a metallic core, a rawhide sheath embracing the core and projecting beyond the ends thereof, rawhide cores fast 105 in the extended portions of the sheath and

flush with the ends of the sheath, and a handle in the metallic core and sheath.

4. In a mallet of the type set forth, the combination of a metallic core, a sheath comprising spiral convolutions of rawhide tightly embracing the core and extending beyond the core, cores comprising spiral convolutions of rawhide fast in the extended

portions of the sheath, rivets extending transversely of the sheath and the last mentioned cores, and a handle in the metallic core and sheath. 10

In testimony whereof I have affixed my signature.

CHARLES W. HOLBROOK.
